JAR TOP REMOVER WITH RESILIENT CAP ENGAGING MEMBER

Filed Sept. 28, 1950

UNITED STATES PATENT OFFICE

2,645,957

JAR TOP REMOVER WITH RESILIENT CAP
ENGAGING MEMBER

Vernon H. Goldsmith, West Palm Beach, Fla.

Application September 28, 1950, Serial No. 187,218

6 Claims. (Cl. 81—3.3)

1

This invention relates generally to kitchen tools, generally speaking, and more particularly to a jar or similar container top remover which can be mounted on a handle and used as a portable tool, or which may be mounted on a bracket fixed to a wall or an equivalent stationary support.

A primary object of the invention is to provide a means for expeditiously removing the tops of glasses and jars such as are ordinarily used as containers for certain types of cheese, olive butter, various brands of jellies, and the like, the containers often being of the type which are usable as drinking glasses after the tops have been removed.

Another object of this invention is to provide means for removing vacuum-type tops so that the top is not deformed and so that the top can be replaced on the jar after a serving has been removed therefrom. In jar top openers of conventional type there is no means provided to prevent the jar tops from bending out of shape during the removal thereof from the jar. The present invention provides such means.

Another object of this invention is to provide a jar top remover which can be used with many different shapes and types of jar tops.

Another object of the invention is to provide an opener of extremely simple form and which is extremely simple to mount in a suitable location in the kitchen, the jar top opener being capable of being disposed either generally horizontally or inclined to the horizontal, by the use of a simple plate or an angle bracket, respectively, as mounting means, and it should also be noted that this invention is ideally adapted for incorporation with a handle so that the tool is made completely portable.

A last object of the invention to be mentioned specifically is to provide a device of this kind which is relatively inexpensive and practicable to manufacture, which is simple and completely safe to use, which is hygienic and easily cleaned, and which will give generally efficient and durable service.

With these objects definitely in view, this invention resides in certain novel features of construction, combination and arrangement of elements and portions as will be hereinafter described in detail in the specification, and particularly pointed out in the appended claims and illustrated in the accompanying drawings which form a material part of this application, and in which:

Figure 1 is a view, in perspective, of one em-

2

bodiment of this invention wherein the jar top opener is secured to a wall by means of a simple plate;

Figure 2 is a fragmentary bottom plan view of the structure of Figure 1;

Figure 3 is a view, in perspective, of a modified form of this invention wherein an angle bracket is used to support the jar and jar top engaging member;

Figure 4 is another view, in perspective, of the structure shown in Figure 3 with the jar top and the upper portion of the jar with said top removed from the jar;

Figure 5 is a view, in perspective showing this invention incorporated with a handle rather than with means for securing the device fixedly on a wall; and

Figure 6 is a fragmentary vertical longitudinal sectional view of the element hereinafter referred to as a bar.

Like reference characters designate like parts throughout the views.

By way of introduction to the detailed description, and, generically speaking, the several embodiments of the invention herein revealed have to do with a part hereinafter called a bar. This is preferably linearly straight and flat throughout its major portion. Either at one end or adjacent to one end said bar is provided with a laterally disposed depending portion and this, in turn, has its free or terminal end fashioned into a hook. The hook underlies the adjacent end portion of the bar. In addition and as will be more specifically set forth, there is a jar top engaging plate which is preferably flat and is substantially coextensive in length with the bar. It underlies the bar and has one end portion either directly or indirectly secured operatively and rigidly to the corresponding end portion of the bar. The plate is resiliently rigid and the unattached end portion is free and is interposed between the hook and the overlying portion of the bar.

Referring now to the drawings in detail, it will first be noted that there are three embodiments of this invention illustrated, Figures 1 and 2 showing one embodiment, Figures 3 and 4 showing another embodiment, and Figures 5 and 6 showing a third.

Referring first to Figures 1 and 2, the bar 10, constructed of rigid material such as a reasonably good grade of steel, is provided at one end with an upturned flange 12 which is secured to an attaching plate 14 by means of rivets 16, although other means of attachment may obviously

be used. The plate 14 is secured to a wall or the like by screws or the like (not shown) inserted through the apertures 18 in the plate 14. The other end of the bar 10 is provided with a depending portion 20 terminating in a returned lip 22, the lip being offset from the bar 10 by the depending portion 20 and the lip extending substantially parallel to the bar 10. The edge of the lip, indicated at 24, disposed toward the attaching plate 14, is arcuate to fit the side of the jar during the operation of removing the top from the jar. Otherwise stated, the hook is made arcuate to conform to and fit under the edge of the jar top.

A jar top engaging plate 26, in the present form of the invention considerably broader than the bar 10, extends underneath this bar 10 and terminates in an attaching flange 28 which is riveted, as at 30, to the attaching plate 14. The other end of the jar top engaging plate 26 rests upon the inner surface of the lip 22 except when sprung away therefrom during the actual operation of the device. In other words, the jar top engaging plate 26 is slightly resilient and the lip 22, aside from its function in engaging the jar top, also serves as a stop to limit the downward movement of the end 32 of the jar top engaging plate 26.

Referring now to the embodiment of this invention illustrated in Figures 3 and 4, it will first be noted that the same general arrangement of elements is maintained in this embodiment. However, the bar 100 has its attaching flange 102 depending instead of upwardly turned and this flange 102 is secured directly to a wall 104, or the like. The other end of the bar 100 is offset from the wall 104 by an angle bracket 106, the flange 108 of which is also secured to the wall 104, so that the upper end of the bar 100 is held outwardly from the wall and the bar is inclined to the vertical. The lip 114 is offset from the bar 100 by a portion 112 and the portion 112 is integral with an attaching flange 110, ordinarily welded directly to the outer surface of the bar 100 near its upper end. The lip 114 corresponds functionally and structurally with the lip 22 already described. In each case, the lip may taper to the arcuate edge thereof, as clearly indicated in the drawings. The jar top engaging plate 116 in this embodiment is provided with a depending flange 118 secured by the screws 120, which screws also are used to hold the flange 102 on the wall 104. The screws 122 are used to secure the attaching flange 108 in place. It will be noted that a jar top 126 is engaged by the jar top engaging plate 116, upon a considerable portion of its upper surface so that deformation of the jar top is prevented, while the jar 124, fragmentarily illustrated in Figure 4, is pried downwardly away from the top 126. The lip 114, of course, engages the one edge of the jar top 126.

In Figures 5 and 6, the third embodiment of this invention is illustrated. In this embodiment, the bar 200 is formed integral or rigidly secured to a handle 202, which handle may be considered the supporting member for the bar 200. The handle 202 will preferably be formed with laterally disposed flanges 204 so that the handle is more comfortable to use, it being understood that any type of handle may be incorporated with this device. Nevertheless, the simple form shown has certain advantages, inasmuch as the cost of production is limited and the tool is very easy to clean. When the tool is held in operative position, the element 206 comprises a depending por-

tion with the lip 208 on its lower end. As before, the element 206 and the lip, together with the handle 202 may be formed as an integral part of the bar 200. The jar top engaging plate 210 is preferably, in this embodiment, slightly wider than the bar 200 and the heel portion of the plate 210 comprises an angulated portion 212 of the plate terminating in an attachment portion 214 which may be welded to the end portion of the handle 202 adjacent the bar 200 so that the main portion of the plate 210 is spaced from the bar 200. As before, the jar top engaging plate 210 will be slightly resilient, or at least the portion 212 thereof should be slightly resilient so that the tool will accommodate itself to use with different sized jar tops. The handle 202 may be formed integral with the hook end of the bar 200 so that the lip 208 is in the middle of the tool.

The operation of this invention will be clearly understood from a consideration of the foregoing description of the mechanical details thereof, taken in connection with the drawings and with the above recited objects. In every case, the jar top is engaged at its edge between the lip and that part of the jar top engaging plate adjacent thereto. The jar is then pried or pivoted, as indicated in Figure 4, and the jar is removed without deformation of the same. Further description would appear unnecessary.

Having described the invention, what is claimed as new is:

1. A container top remover comprising a longitudinally elongate rigid bar, one end of which is adapted to be fixedly joined to any suitable support means, the other end portion of said bar having a lateral depending rigid portion integrated therewith and terminating in a rigid right angled return bend underlying said other end portion of the bar in spaced relationship therewith and defining a container top engaging and lifting lip, a container top bridging and contacting plate underlying and opposed to said bar, means affording a rigid and permanent connection between one end of said plate and the corresponding end of said bar, the other end of said plate being free and interposed in the space between said lip and the adjacent overlying end portion of said bar, said plate being flexibly resilient, constituting a container top anti-distorting brace, and being adapted to reside in firm stabilizing contact with said container top from one side to the other diametrically opposite side of the latter, whereby when said lip is engaged with the usual rim of said top and the latter is dislodged and pried off, the brace acts to prevent the body portion of said top from bending or otherwise becoming distorted in shape.

2. The structure defined in claim 1, wherein the underneath side of said bar is flat and linearly straight, said plate having flat top and bottom surfaces and being of a length and width to cooperate with container tops of a wide range of diameters, the free end of said lip being arcuately curved and said lip having the additional function of a stop so that the free flexing end of said plate is at all times confined in the space between said lip and the overlying end portion of said bar.

3. A jar top remover comprising, in combination, a supporting member, a bar rigidly secured at one end to said supporting member, the other end portion of said bar having a laterally disposed depending portion terminating in a right angularly disposed return bend underlying said bar in spaced relationship therewith and providing a jar top engaging lip, a resilient jar top en-

gaging plate extending underneath of said bar and means rigidly securing one end of said plate to said supporting member, the other end of said plate being interposed between said lip and the adjacent overlying portion of said bar.

4. A jar top remover comprising, in combination, a supporting member, a bar rigidly secured at one end to said supporting member, the other end of the bar having a laterally disposed portion terminating in a right angularly disposed return bend underlying the adjacent end portion of the bar in spaced relationship therewith and providing a jar top engaging lip, and a resilient jar top bridging and contacting plate substantially commensurate in length with said bar and underlying the bar in spaced relation and rigidly secured at one end to said supporting member, the other end of said plate being free and confined for functioning in the space between said lip and the overlying portion of the bar, said supporting member being a flat attachment plate which latter is adapted, when in use, to be superimposed upon and fixedly secured to a relatively stationary wall or the like.

5. A jar top remover comprising an elongate rigid bar having one end adapted to bear against and to be secured to a relatively stationary support, said bar extending angularly from said support, the other end portion of said bar being spaced from said support and having an angle bracket formed integrally therewith, said angle bracket having an end adapted to be secured to the same support, said bar and complementary angle bracket conjointly forming a substantially V-shaped fixture, said other end portion of said bar having a laterally directed portion formed integrally therewith and provided with an angularly disposed terminal bend underlying the bar in approximate spaced relationship and co-operating therewith in providing a jar top engaging and lifting lip, and elongate resilient jar top bridging plate of a length slightly less than the length of said bar and underlying the underneath side of said bar, said plate being adapted to firmly contact and stabilize the jar top when

5 the latter is being dislodged and lifted for removal, one end of said plate being rigidly secured to the corresponding end of said bar, the opposite end of said plate being free, situated in the space between said lip and adjacent end portion of the bar and being bendable toward and from the bar, said lip constituting a stop for the free end portion of said plate so that the latter is constantly confined in the space between the lip and bar.

the latter is being dislodged and lifted for removal, one end of said plate being rigidly secured to the corresponding end of said bar, the opposite end of said plate being free, situated in the space between said lip and adjacent end portion of the bar and being bendable toward and from the bar, said lip constituting a stop for the free end portion of said plate so that the latter is constantly confined in the space between the lip and bar.

6. A jar top remover comprising a supporting member, a flat faced linearly straight rigid bar secured at one end to an adjacent end of said supporting member, the other end of the bar having a laterally disposed depending portion terminating in a return bend disposed in spaced relationship to the adjacent end portion of the bar and providing a jar top engaging and lifting lip, said bar and supporting member being axially aligned and coplanar and said supporting member being shaped properly and functioning as a handle, and a flexibly resilient jar top brace, the latter being in the form of an elongate plate of a length substantially commensurate with the length of the bar and underlying the bar, one end of said plate being rigidly secured at the juncture of said bar and handle, the opposite end of the plate being freely bendable toward and from said bar and being situated in the space between said lip and the overlying end portion of said bar, whereby to provide a portable jar top remover.

VERNON H. GOLDSMITH.
